UNITED STATES PATENT OFFICE.

CLYDE C. FARMER, OF PITTSBURGH, PENNSYLVANIA, ASSIGNOR TO THE WESTINGHOUSE AIR BRAKE COMPANY, OF WILMERDING, PENNSYLVANIA, A CORPORATION OF PENNSYLVANIA.

ELECTRIC TRAIN-WIRE COUPLER.

Application filed June 14, 1922. Serial No. 568,245.

This invention relates to couplings for connecting electric circuits between cars of a train, and more particularly to the type of electric coupling employing a movable contact carrier having a plurality of contacts adapted to engage corresponding contacts in the counterpart coupler head when the contact carrier is projected.

One object of my invention is to provide an electric coupler of the above character in which mechanical means operated by the coming together of the counterpart couplers operates to project the contact carrier and in which the mechanical means exerts substantially no pressure in the coupled position tending to separate counterpart coupler heads.

The above is of importance where an electric coupler is associated with a car coupler of the tight lock type, since mechanical tappets or push bars operated by the coming together of counterpart couplers and exerting pressure tending to interfere with the full closing movement of the electric couplers will also tend to prevent the movement of the car coupler locking levers to the fully locked position.

Another object of my invention is to provide a mechanical means operated by the coming together of counterpart couplers for projecting the contact carrier and having means for operatively disconnecting the mechanical means from the contact carrier.

Another object of my invention is to provide means for operatively disconnecting the contact carrier operating means from the contact carrier in the projected coupled position and means for locking the contact carrier in its projected position.

Another object of my invention is to provide an electric train line coupler in which machining is reduced to a minimum and in which most of the assembling and working connections may be cored or cast in the parts.

Other objects and advantages will appear in the following more detailed description of the invention.

In the accompanying drawings; Fig. 1 is a horizontal section on the line 1—1 of Fig. 2 of an electric train line coupling embody-

ing my invention; Fig. 2 a section on the line 2—2 of Fig. 1; Fig. 3 a diagrammatic view, showing the relative positions of the electric contacts of counterpart coupler heads upon initial engagement; Fig. 4 a section on the line 4—4 of Fig. 1; Fig. 5 a section on the line 5—5 of Fig. 1; Fig. 6 a section on the line 6—6 of Fig. 1; Fig. 7 a section on the line 7—7 of Fig. 1; Fig. 8 a partial plan view of the electric coupler, partly broken away to show the fluid pressure passages; Fig. 9 a detail sectional view of one of the stationary or fixed electric contact elements; Fig. 10 a detail sectional view of one of the movable electric contact elements; Fig. 11 a fragmentary elevational view of the electric coupler head, showing the contact shielding door in the open position; Fig. 12 a section of a portion of the electric coupler head, partly on the line 4—4 and partly on the line 12—12 of Fig. 1, to show the final coupled positions of the door and contact carrier operating mechanisms; Fig. 13 an end view of one of the contacts; Fig. 14 a detail side view, showing the hand lever link support; and Fig. 15 a detail end view of the link support.

The electric coupler head shown in the drawings is designed to be bolted to the underside of a car coupler head and is more especially adapted for use in connection with a car coupler such as shown in Patent No. 708,747 of George Westinghouse, dated September 9, 1902, and in which there is a relative lateral movement of the coupler heads in the act of coupling.

The coupler head may comprise a casing 1 containing a movable contact carrier 2 which is pivotally supported by three links 3, the two front links 3 being mounted to swing on trunnion pins 4 carried by the casing and being pivotally connected to pins 5 carried by the contact carrier 2. The central rear link 3 is supported by a pin 6 and is pivotally mounted on a pin 7 carried by the contact carrier. The above described link support construction permits a swinging movement of the contact carrier in the act of projecting and retracting the same.

In order to prevent lateral movement of the contact carrier 2 front and rear guide

links 8 and 9 may be provided which are pivotally mounted at one end on the side wall of the casing and are pivotally connected at the other end to the contact carrier.

The force for projecting the contact carrier is obtained by the movement of a push rod 10 through impact with the meeting face of a counterpart coupler head in the act of coupling. The push rod 10 is mounted in bearings 11 provided in the casing 1 and is operatively connected at the rear end by links 12 to rocker arms 13. Intermediate the rocker arms 13 is a notched disk 14 having hub extensions forming bearings for the rocker arms 13 and pivotally mounted on and between the rocker arms is a pawl 15 adapted to engage in the notch of the disk 14. A spring 63 on the pivot pin 64 serves to yieldingly press the pawl 15 into engagement with the disk 14.

The notched disk 14 is mounted on a squared shaft 16 and on one end of the shaft is mounted a depending rocker arm 17 having a hub 18 which works in a bearing formed in the casing 1. At the other end of the shaft a rocker arm 19 is mounted having a hub 20 which rests in a bearing in the casing, so that the hubs 18 and 20 provide rotatable bearing supports for the square shaft 16. The arm 17 carries a pin 21 which engages in a slot 22 of a link 23, the forward end of the link being pivotally connected to the contact carrier 2 through a pivot pin 24 which extends through the contact carrier. The other rocker arm 19 is pivotally connected to one end of a link 25, the other end of which is pivotally connected to the contact carrier through the same pivot pin 24. It will thus be seen that the rocker arms 17 and 19 and the links 23 and 25 form toggle joints through which the contact carrier 2 is projected when the shaft 16 is rotated.

The rotation of the shaft 16 is also employed to operate a door 26 which protects the contacts of the contact carrier from exposure to the elements when the car is uncoupled and the door is closed. For this purpose, a square door operating shaft 27 is provided which is mounted in rotatable bearing members 28 adapted to operate in bearings provided in the side walls of the casing 1. Carried by the shaft 27 is a rocker arm 29 having rotatably mounted therein a roller 30 and for actuating the roller 30, a push bar 31 is provided one end of which engages the roller in the uncoupled position of the parts and having the other end pivotally connected to the rocker arm 17 as more clearly shown in Fig. 4. The bar 31 is disposed between guide rollers 32 and is so shaped that after the shaft 27 has been rotated through the desired angle

by the engagement of the bar with the roller 30, said bar will ride over the roller and then lock and prevent retractive movement of the shaft.

The bearing elements 28 at opposite ends of the shaft 27 are each provided with an arm 33 having pivotal connection with the door 26 through an extended pivot pin 34. Pins 35 are secured to the opposite upper side portions of the door 26 and extend into vertical slots 36 formed in the casing 1 at the contact face of the coupler head, so that the upper end of the door will move vertically when the door is operated while the lower end of the door swings rearwardly with the arms 33.

A coil spring 37 is mounted on the shaft 27 and has one end held by a pin 38 on the shaft, and the other end of the spring engages the bottom wall of the casing 1, so that the spring acts torsionally on the shaft 27 to yieldingly maintain the door in its closed position.

The contact carrier 2 comprises a casing in which is mounted moulded blocks 39 and 40 of insulating material containing vertical rows of contacts. At one side of the central row of contacts, the contacts may be of the stationary type and at the other side of the movable compression type, since it is only necessary for one contact of two coacting contacts to be of yielding character in order to provide the necessary yielding movement when companion contacts of counterpart coupler heads engage in the act of coupling. The central row of contacts, however, are of the yielding type.

As shown more clearly in Fig. 9 of the drawings, each stationary contact may comprise a butt contact member 41 mounted in the insulation block 40 and having a rear bolt extension 42 with a nut 43 and a jam nut 44 for securing the contact member in the block of insulation. In the block of insulation 39 there is secured by a nut 45 and a jam nut 46 a terminal member 47 having a split contact portion 48 adapted to slidably engage in a sleeve 49 which contacts with the jam nut 44 and is held in position by a spring 50. The contact face of the contact member 41 is preferably made square instead of round so as to provide a greater contact area and thus reduce the arcing tendency when contacts are separated or brought together. In order to reduce to a minimum the tendency of the electric current to creep from one contact to another, insulation 51 is moulded in a recess formed in the contact member 41.

As shown more clearly in Fig. 10 of the drawings, each movable contact may comprise a butt contact member 41' which is provided with a rear sleeve extension 52 movable in a sleeve 53. Between the mem-

ber 41' and a nut 54 screwed into the sleeve 53 is a coil spring 55 for yieldingly maintaining the contact member 41' projected. The contact sleeve 49 engages the nut 54 and the terminal contact portion is similar to that of the stationary contact, except that the terminal 47' may be provided with a rear opening for receiving a split contact 56 attached to the train wire. The contact 10 blocks 39 and 40 may be secured in place by means of a frame 57 which is secured to the casing 2 by means of bolts 58. The cable containing the train wires connected to the respective contacts of the contact 15 carrier is held in position by means of a cable clamp comprising clamping segments 59 which are clamped to the cable by means of a cable sleeve 60 which is secured to the rear portion 61 of the carrier casing 2 by bolts 20 62. A coil spring 65 is interposed between a portion of the casing 1 and a projection 66 of the contact carrier 2 for the purpose of retracting the contact carrier when cars are uncoupled.

25 In operation, when the counterpart coupler heads are brought together in the act of coupling before the faces of the coupler heads meet the end of the push rod 10 will engage the meeting face of the counterpart 30 coupler head. The push rod 10 is then pushed rearwardly and through the links 12 rotates the rocker arm 13 and the pawl 15. The pawl 15 engaging the notched disk 14 rotates the disk and the square shaft 16.

35 The rocker arm 17 is thus rotated to project the door operating bar 31. The bar 31 pushes the roller 30 of the rocker arm 29 and thereby rotates the door shaft 27 so that the connected arms 33 cause the door 26 to be shifted to its open position, as shown in Fig. 11. When the door has assumed its full open 40 position, the angular position of the roller 30 will be such that the bar 31 will ride over the roller to the position shown in Fig. 12, which will result in locking or holding the door 26 in its fully opened position. The 45 guide pins 35 of the door 26 operating in the grooves 36 causes the upper portion of the door to move vertically downward and also serve as a hinge for permitting the lower portion of the door to swing inwardly and rearwardly.

50 At the same time the above door opening operation is taking place, the pivot pin 21 of the rocker arm 17 is moving in the toggle link slot 22 until at about half its travel, the pin engages a spring stem 67. Further movement of the pin 21 compresses spring 68.

55 During this movement, the link 23 is being raised and when the pin reaches the end of the slot 22 the link 23 will be pushed forward and being connected to the contact carrier 2, the carrier is projected outwardly to its contact position.

During this movement, the retrieving spring 65 is being compressed and when the center of the pin 21 passes slightly above the center line of the shaft 16 and the pivot pin 24, the spring 65 will act to slightly retract the contact carrier and continue the upward movement of the toggle link independently of the push rod 10, until the link 23 engages a stop 69, as shown in Fig. 12. At about the same time the above operation 70 is occurring, the outer end of the pawl 15 75 will engage a stop 70, so that further inward movement of the push rod 10 causes the pawl 15 to be thrown out of engagement with the notched disk 14, as shown in Fig. 12.

80 It will now be seen that in the coupled position, the push rod 10 being tripped out of engagement with the notched disk 14 is not subjected to any pressure and therefore does not exert any pressure against the face of the counterpart coupler head in the coupled position and that movement of the push rod in the coupled position will not be transmitted to the contact carrier, so that there 85 will be no variation in the contact pressure.

85 The contact carrier in the coupled position being held practically rigid by the action of the release spring 65 pressing the contact carrier rearwardly, so that the link 90 95 23 acts as a stop, the contacts will be held in engagement only by the force of the individual spring of each movable contact.

90 When the above described electric coupler is attached to a car coupler of the type having a relative lateral movement in the act of coupling, the contact points will initially engage off center, as illustrated in Fig. 3. As the coupling movement continues, the contact points move laterally with the car 100 105 coupler, so that a lateral wiping action takes place until in the final coupled position, corresponding contacts are in alinement. By this action the contact engaging surfaces are maintained bright and smooth.

110 Surrounding the exposed contact points is a flexible weather strip 71 which engages a corresponding weather strip of the counterpart contact carrier when in coupled position, so as to protect the contacts against weather and against the entrance of foreign substances. Entrance of dirt and moisture into the coupler casing is prevented by another weather strip 72 which is carried by the frame 57 and is adapted in the coupled 115 120 position to engage an inner face 73 of the casing 1.

125 In order to uncouple, means are provided for throwing the toggle joint to the opposite side of the center line of the shaft 16 and the pin 24 such as a piston 74 having a stem 75 adapted to engage the link 23. Fluid under pressure may be supplied to the piston 74 by means of a manually operated valve 76 located in the cab. The valve 76 130

may be provided with a through port 77 and a cavity 78 and normally the valve 76 is positioned so that cavity 78 connects piston 74 through passage 79, passage 80 and pipe 81 with an exhaust port 82.

When it is desired to uncouple, the valve 76 is turned so that the through port connects a source of fluid pressure supply pipe with pipe 81 and fluid under pressure being thus admitted to piston 74, the piston is shifted to cause the stem 75 to force the toggle link 23 downwardly past the center line of the toggle joint. As soon as the toggle joint passes the center line, the spring 63 acts to retract the contact carrier to its release or uncoupled position. When fluid is supplied to the piston 74 of the electric coupler on the operating car, fluid also flows through passage 80 to a tappet 84 at the face of the coupler which engages a corresponding tappet of the counterpart coupler head, so that fluid under pressure flows through the engaging tappets 84 to the piston 74 of the counterpart coupler head, thus causing the retracted movement of the contact carriers of both coupler heads.

As the link 23 passes the center line of the toggle joint, the spring 68 expands and throws the pin 21 forward, together with the rocker arm 17 and the door member 31 so that at a given angular position of the link 23, the end of the member 31 will slip by the roller 30, permitting the pressure of the torsional spring 37 on the door shaft 27 to be exerted through the roller 30 to push the member 31 and the rocker arm 17 back to the normal uncoupled position. The rotation of the door shaft 27 by the action of the torsional spring 37 operates to move the door 26 to its closed position so as to protect the contact from exposure to the weather and prevent entrance of dirt and foreign matter into the coupler head when the car is uncoupled. When the piston 74 has moved down its full stroke and the contact carrier has been retracted as above described, fluid under pressure is supplied from passage 79 past the piston 74 to pipe 85 which is connected to the car coupler unlocking cylinder (not shown) so that the car couplers are not uncoupled until the contact carriers have been retracted. Rearward movement of the contact carrier may be limited by the engagement of the rear suspending link 3 with a pin 110.

When the cars are separated, the push rod 10 will be moved outwardly by the spring 86, causing the rotation of the rocker arms 13 and the pawl 15 to the normal uncoupled position as shown in Fig. 4.

It is sometimes desirable to provide for local car circuits which are closed when a car is uncoupled, such as a tail light circuit, a rear door locking circuit, or the like, and for this purpose a rear contact mechanism

is provided by which local circuits may be opened when the contact carrier is projected and closed when the carrier is retracted. According to my invention there is mounted on the shaft 16 one or more contact carrying members comprising a metal sleeve 112 having mounted therein insulation 88 and moulded in the insulation are contacts 87, the contact member being positioned on the shaft by means of a cotter pin 106.

The rear end of the contact carrier 2 has secured thereto one or more blocks of moulded insulation material 90 carrying spring contacts 89, a pair of spring contacts 89 being adapted to engage one of the contacts 87 to close a corresponding car circuit.

In the act of coupling, the shaft 16 rotates through a certain angle before the contact carrier 2 is moved forward, as hereinbefore explained, so that the contact 87 is initially rotated out of engagement with the corresponding spring contacts 89 by a wiping movement which tends to maintain the contacts bright and smooth at the line of contact used in carrying current in the uncoupled position of the parts, any arcing which may occur being at a point not used in carrying current, due to the rotation of the shaft contact member. A similar wiping action occurs when the parts are moved to the uncoupled position in which the contact carrier 2 is retracted and the contacts 89 are moved rearwardly to engage the contact 87.

In order to permit the contact carrier to be retracted from its coupled position while the cars remain coupled up, a manually operable lever arm 91 is provided, which is loosely mounted on the bushing member 20 of the shaft 16. A pin 98 projects from the shaft 16 and through the bushing 20 and the hub of the lever 91 is provided with a bayonet slot 99 in which the pin 98 is adapted to operate. When not in use the end of the hand lever 91 may be supported by a loose link 100, as shown in Figs. 14 and 15, with the pin 98 in the elongated portion of the slot 99. When it is desired to manually retract or project the contact carrier, the hand lever 91 is disengaged from the link 100 and is moved downwardly and at the same time is pressed laterally outward, so that in the alining position, the pin 98 will engage in the bayonet portion of the slot 99, as shown in Fig. 8, the further movement of the lever 91 will now effect the rotation of the shaft 16, so that through the connecting parts, the contact carrier may be either retracted or projected.

If it is desired to leave the contact carrier in its retracted position, the lever 91 may be disengaged from the pin 98 by pressing the lever inwardly and then the lever may be turned without rotating the shaft and secured out of the way by hooking the link 100 over the end of the lever.

In order to provide access to the interior of the coupler head for repairs or the removal and replacement of parts the lower rear portion of the housing 1 is cut away, as shown in Fig. 12 and a cover plate 95 of sheet steel is provided for closing the opening in the casing.

A groove 105 is provided in the under end of the vertical walls of the housing 1 and a horizontal ledge 96 is provided as shown and the cover plate 95 is applied by placing the lower edge of the plate on the ledge 96 and inserting the upper edge in the groove 105. When in position, the plate 95 is secured to the housing by means of cap screws 97. The groove 105 and the ledge 96 serve both as a cover holder and as a weather and dust proof joint.

The through pin 24 which connects the contact carrier 2 with the links 23 and 25 at opposite sides of the contact carrier may be made adjustable by mounting the same in adjustable eye bolts 101 secured to the carrier and the adjustment may be effected by inserting or taking out one or more shim washers 102 interposed between the head of the eye bolt and the supporting lug 103 of the contact carrier.

The stop 70 may be in the form of a stud, so that the position may be adjusted by screwing the stud in or out as desired.

Since the contact carrier swings on links, the carrier will have a vertical movement as it swings and consequently, when a contact carrier is manually projected or retracted by the operation of the hand lever 91, there will be a vertical wiping action as the contacts engage or disengage from the contacts of the counterpart coupler, so that the contact faces are cleaned of dirt by this action when operating manually.

When the train wire cable is clamped in position, the segments 59 are forced into the cable by drawing the sleeve 60 into engagement with the portion 61 and the meeting faces of the sleeve 60 and the portion 61 being in engagement the sleeve is accurately aligned with the contact carrier and at the same time the cable is firmly held in position. A dust excluding washer 104 is slidably mounted on the sleeve 60 and extends into a slot 105 in the rear wall of the casing 1.

By employing a square shaft 16 the proper positioning of the members applied to the shaft is always assured and said shaft may be cold rolled stock not requiring any machining or key ways.

The tappet 84 is slidably mounted in a bushing 107 and the outward movement thereof is limited by a spring ring 108 engaging in a groove in the tappet so that to apply the tappet in position it is only necessary to place the spring 109 in the tappet cavity of the casing 1 and then screw the bushing into the casing, as shown in Fig. 2.

In operating the coupler mechanism so as to retract the contact carrier and close the shutter or door 26, it might be possible for the contact carrier to stick and fail to move from its contact position to its retracted position, although the door 26 might be moved and might engage and damage the projected contacts. In order to prevent such an occurrence, the outer frame member 57 of the contact carrier 2 may be provided with horizontally projecting lugs 111 at opposite sides of the frame, as shown in Fig. 11.

When the contact carrier is in its projected position and the door 26 in its open position, the lugs 111 extend over the top edge of the door, so that the door can not move vertically upward toward the closed position until the contact carrier has been retracted, and the lugs 111 are withdrawn out of the path of the door.

From the foregoing description, it will be seen that very little machine work is required, other than the drilling of holes and that machined guides for the contact carrier are dispensed with by employing the link suspension to provide for the longitudinal movement of the contact carrier.

In order to hold the shaft 16 in position in the coupler head, a circular groove 113 is turned near the end of the shaft, as shown in Fig. 7 and after the shaft has been placed in position, a yoke 114 is slipped over the shaft in the groove 113, the yoke being then secured to the casing 1 by means of cap screws 115, as shown in Fig. 1.

Having now described my invention, what I claim as new and desire to secure by Letters Patent, is:—

1. An electric train line coupler comprising a movable contact carrier, a push rod operable by the coming together of counterpart couplers, a rotatable shaft, a pawl operated by said push rod for rotating said shaft, an arm rotatable with said shaft, and a link connecting said arm with the movable contact carrier.

2. An electric train line coupler comprising a movable contact carrier, a push rod operable by the coming together of counterpart couplers, a rotatable shaft, a pawl operable by said push rod, a pawl engaging member carried by said shaft, an arm rotatable with said shaft, and a link connecting said arm with the movable contact carrier.

3. An electric train line coupler comprising a movable contact carrier, a rotatable shaft, means operated upon rotation of said shaft for projecting said contact carrier, a member rotatable with said shaft, a pawl engaging said member, a push rod operated by the coming together of counterpart couplers for operating said pawl to rotate said shaft and thereby project said contact carrier, and means for engaging and tripping

said pawl out of engagement with said member upon a predetermined movement of said push rod.

4. In an electric train line coupler, the combination with a movable contact carrier, of a mechanical connection actuated by the coming together of counterpart couplers for projecting said contact carrier, means for operatively disconnecting the contact carrier from the mechanical connection in the coupled position, and means for retracting the contact carrier while the counterpart couplers are in the coupled position.

5. In an electric train line coupler, the combination with a movable contact carrier, of a mechanical connection actuated by the coming together of counterpart couplers for projecting said contact carrier, means for disconnecting the contact carrier from the mechanical connection during the final coupling movement, and means for retracting the contact carrier while the counterpart couplers remain in the coupled position.

6. In an electric train line coupler, the combination with a movable contact carrier, of a mechanical connection actuated by the coming together of counterpart couplers for projecting said contact carrier, means for disconnecting the contact carrier from the mechanical connection during the final coupling movement, and manually controlled means for retracting the contact carrier while the counterpart couplers are in the coupled position.

7. In an electric train line coupler, the combination with a movable contact carrier and a spring for opposing the projection of said carrier, of a mechanical connection actuated by the coming together of counterpart couplers for projecting said contact carrier and means for locking said contact carrier against retractive movement from the coupled position to thereby relieve the mechanical connection from the pressure of said spring.

8. In an electric train line coupler, the combination with a movable contact carrier and a spring for opposing the projection of said carrier, of a mechanical connection actuated by the coming together of counterpart couplers for projecting said contact carrier, means operative during the final coupling movement for disconnecting the contact carrier from the mechanical connection, and means for locking said carrier against retractive movement to thereby relieve the mechanical connection from the pressure of said spring.

9. In an electric train line coupler, the combination with a movable contact carrier and a spring for opposing the projection of said carrier, of a toggle lever mechanism comprising a link connected to the contact carrier and a rocker arm, a pawl for actuating said rocker arm, and a push rod oper-

ated by the coming together of counterpart couplers for actuating said pawl, the toggle lever mechanism being movable by the push rod to a position in which said spring operates to release the rocker arm from said pawl.

10. In an electric train line coupler, the combination with a movable contact carrier and a spring compressed by the projection of the contact carrier, of a toggle lever mechanism operatively connected to said contact carrier, means for actuating said toggle lever mechanism to project said carrier, and a stop engaging said toggle lever mechanism upon a further movement of said mechanism to prevent retraction of the contact carrier by said spring.

11. In an electric train line coupler, the combination with a movable contact carrier and a spring for opposing the projection of said carrier, of a toggle lever mechanism connected to the contact carrier, means operated by the coming together of counterpart couplers for moving said toggle lever mechanism to its line and line position to project the contact carrier, and a stop for limiting the further movement of the toggle lever mechanism by the action of the spring to a position slightly in advance of said line and line position.

12. In an electric train line coupler, the combination with a movable contact carrier and a spring for opposing the projection of said carrier, of a toggle lever mechanism connected to the contact carrier, means operated by the coming together of counterpart couplers for moving said toggle lever mechanism to its line and line position to project the contact carrier, a stop for limiting the movement of the toggle lever mechanism past its line and line position, and means for moving said toggle lever mechanism to the other side of its line and line position to permit the retraction of the contact carrier by the spring.

13. In an electric train line coupler, the combination with a movable contact carrier and a spring for opposing the projection of said carrier, of a toggle lever mechanism connected to the contact carrier, means operated by the coming together of counterpart couplers for moving said toggle lever mechanism to its line and line position to project the contact carrier, a stop for limiting the movement of the toggle lever mechanism past its line and line position, and manually operated means for effecting the reverse movement of the toggle lever mechanism across the line and line position to thereby permit the contact carrier to be retracted by the action of the spring.

14. In an electric train line coupler, the combination with a movable contact carrier, of mechanical means actuated by the coming together of counterpart couplers for

projecting said carrier and means for operatively disconnecting said mechanical means from the contact carrier during the final movement to the coupled position to permit movement of the contact carrier relative to said mechanical means.

15. In an electric train line coupler, the combination with a movable contact carrier and a spring for opposing the projection of said carrier to the coupled position, of mechanical means actuated by the coming together of counterpart couplers for projecting said carrier and means for relieving said mechanical means of the reactive pressure of said spring during the final movement to the coupled position to thereby facilitate the full movement of the coupler to its coupled position.

16. In an electric train line coupler, the combination with a casing, of a movable contact carrier, links for vertically suspending said carrier in the casing to swing longitudinally, and other links connected to the carrier for preventing lateral movement thereof.

17. In an electric train line coupler, the combination with a movable contact carrier, of a shaft operatively connected to said carrier, contacts carried by said shaft, and contacts carried by the contact carrier and connected to train line circuits and adapted to engage the shaft contacts when the contact carrier is retracted.

18. In an electric train line coupler, the combination with a casing and a movable contact carrier therein, of a movable door for closing the casing, means pivotally connected to the lower edge of the door for swinging the door downwardly and inwardly and means for guiding the upper edge of the door to move vertically.

19. In an electric train line coupler, the combination with a movable contact carrier, of a shaft operatively connected to said carrier, a tappet operatively connected to said shaft and operated by the coming together of counterpart coupler heads for actuating said shaft, a door for protecting the contact carrier, and means associated with said shaft for operating the door.

20. An electric train line coupler comprising a casing, a movable shutter for closing said casing, a rocker arm connected to said shutter, a member connected to said arm, a rotatable shaft, a lever carried by said shaft, and a push bar pivotally connected to said lever and engaging said member, said member being actuated by said push bar to oper-

ate said shutter upon initial rotation of said shaft and said member being turned to a position in which the push bar rides over same.

21. In an electric train line coupler, the combination with a movable contact carrier, a rotatable shaft, and means operated by said shaft for projecting said carrier, of a contact carried by said shaft and a contact carried by the contact carrier for engaging said shaft contact.

22. In an electric train line coupler, the combination with a movable contact carrier, a rotatable shaft, and means operated by said shaft for projecting said carrier, of a contact member comprising a sleeve mounted on said shaft, insulating material carried by said sleeve, and a contact mounted in said insulating material.

23. In an electric train line coupler, the combination with a movable contact carrier, a rotatable shaft, and means operated by said shaft for projecting said carrier, of a contact member mounted on said shaft and including a contact and a yielding contact carried by the contact carrier for engaging said shaft contact.

24. In an electric train line coupler, the combination with a movable contact carrier, a rotatable shaft, and means operated by said shaft for projecting said carrier, of a contact member mounted on said shaft and including a contact and a yielding contact carried by the contact carrier for engaging said shaft contact upon retraction of the contact carrier.

25. In an electric train line coupler, the combination with a movable contact carrier, a rotatable shaft, and means operated by said shaft for projecting said carrier, of a contact carried by said shaft and a contact carried by the contact carrier for engaging the shaft contact, said shaft having a rotative movement preliminary to the projection of the contact carrier whereby a wiping action is produced between said contacts.

26. In an electric train line coupler, the combination with a casing and a movable contact carrier mounted in said casing, of a square rotatable shaft, means operated by said shaft for projecting said contact carrier, a circular groove in a projecting end of the shaft, and a yoke mounted in said groove for holding said shaft in position.

In testimony whereof I have hereunto set my hand.

CLYDE C. FARMER.
